CLAIM

The ornamental design for an electric bottle brush, as shown and described.

DESCRIPTION

FIG. 1 is a front, left, top perspective view of an electric bottle brush, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a front, left, top perspective view shown in a first environment of use;

FIG. 10 is a front, left, top perspective view shown in a second environment of use; and,

FIG. 11 is a front, left, top perspective view shown in a third environment of use.

In FIGS. 1-7, the dashed broken lines illustrate portions of the electric bottle brush and form no part of the claimed design. The dashed broken lines in FIGS. 9-11 are directed to environment of the bottle brush and form no part of the claimed design.
